AUTOMATIC LOUVER

William A. Pledger, San Francisco, Calif.

Application September 27, 1947, Serial No. 776,447

1. Claim. (Cl. 98—119)

1

This invention relates to an automatic louver and to its installation in an exhaust pipe.

The object of this invention is to provide a new automatic louver in which the blades are arranged in a staggered inclined row wherein the free end of each blade rests by its weight on the subsequent blade.

Another object of this invention is to provide means for freely connecting the blades for simultaneous closing or opening of the same either by the current of air flowing therethrough or manually.

Another object of this invention is to provide a new installation of said louver in the exhaust pipe so that the exhausted air will preserve its direction of motion after leaving the pipe for some distance and will be dissipated in the atmosphere without settling down.

Other objects and advantages will appear as the specification proceeds and the particular features of the invention will be specifically pointed out in the appended claim.

My invention is illustrated in the accompanying drawing in which

Fig. 1 is a front view of said louver, some parts being shown in section.

Fig. 2 is a vertical cross-section taken along the line 2—2 of the Fig. 1.

Fig. 3 is a side view of an exhaust pipe showing the installation of the louver.

Fig. 4 is a perspective view of a detail showing the means interconnecting the blades.

Fig. 5 is an enlarged sectional view taken along the line 5—5 of the Fig. 2.

In detail, my louver 1 consists of a frame 2 preferably made of metal and representing a metal band bent to form a square. The frame 2 is open on the front and on the back and has the sides 3 and 4, a top 5 and a bottom 6.

The frame 2 has a plurality of blades 8 preferably made of sheet metal and arranged horizontally within said frame in a staggered slightly inclined row. Each blade 8 is attached to a shaft 10 by bending the top of said blade over said shaft. The latter are rotatably supported by the sides 3 and 4 by having the ends of each shaft 10 protrude through the holes 11 in said sides. The blades 8 are arranged in said frame 2 at a slight angle to the vertical axis and for that reason the lower end of the blade rests by its weight on the top of the subsequent blade with the exception of the lowermost blade which rests on the bottom 6 of the frame. By this arrangement the louver 1 remains normally closed and does not admit any current of air exerting pressure on its face side 12,

2

but the blades are readily opened by a slight current moving in the opposite direction in proportion to the air pressure exerted thereupon, and automatically close when the air flow stops.

5 To insure the opening of all the blades 8 simultaneously, the same are interconnected by a rod 14 extending from the bottom 6 to and through a slot 13 in the top 5 a certain distance and terminating with a loop 15. The rod 14 is connected 10 to the blades 8 by a plurality of wire loops 16 each of which passes through a hole 17 in said rod and through a hole 18 in the lower end of said blade.

If any of the shafts 10 should be deprived of 15 its freedom of rotation in the holes 11 for any reason, such as accumulation of dirt, it will be freed by the pressure exerted on said blade by the rest of them through said rod 14.

If all the shafts 10 should become stuck in their 20 respective holes, they may be freed by manual operation of said rod 14.

The ends of the shafts 10 are enclosed in channel shaped covers 20 which are riveted to the outer surface of the sides 3 and 4. The tops and 25 the bottoms of said covers are closed, as shown at 21 and 22 respectively, to prevent escape of gases and odors from the louver and also to prevent dust and dirt from entering and accumulating in the space between said covers and the sides which 30 may result in freezing the shafts 10 in their holes 11.

Means is provided to prevent the escape of gases 35 and odors through the slot 13 in the top 5, said means comprising a plate 25 slidably arranged in the guides 26 riveted to the inner surface of said top, through which plate the rod 14 freely passes.

The louver 1 is installed in an exhaust pipe 30 a certain distance from the discharge end 31 thereof, said distance being substantially equal to the height of said louver. The exhaust pipe 30, which is round in cross-section, has its portion 32 formed to fit the square frame 2 of the louver, to which it is attached by rivets, or bolts 33. The discharge section 34 of the exhaust pipe, attached 40 to the other end of said louver, is substantially square in cross-section and has its bottom 35 inclined downwardly toward the discharge end 31 and then is turned upwardly a short distance, as shown at 36. A plurality of drip holes 37 is provided in the lowermost portion of the bottom 35.

The bottom 35 is given the above described shape for two purposes: firstly, to drain the water which may collect in the discharge section 34 and permit it to be discharged through the holes 37 45 provided outside the wall 40 through which said

section 34 projects; and, secondly, to divert a portion of the stream of discharged air upwardly by the bottom portion 36, and thereby to neutralize the action of the blades 8 which have a tendency to send the flow of air downwardly by deflecting the air passing therethrough in the latter direction. The shape of the bottom 35 thus forces the air flow to move substantially horizontally and dissipate in the air, thus preventing air from flowing downwardly upon the passing public as is often the case.

I claim:

An automatic louver comprising a substantially rectangular open frame; a plurality of blades arranged therein in a staggered inclined row so that the bottom of each preceding blade rests against the top of the succeeding blade; a shaft journalled in the sides of said frame for the support of each blade, said blades being attached to said shafts; each of said shafts having ends protruding through the sides of said frame a certain distance; means for enclosing said shaft ends, a rod extending parallel to the blades and being connected thereto, the top of said rod projecting through a slot in the top of said frame, and a plate covering said slot, said rod passing through said

plate and adapted to move said plate over said slot.
